ATTORNEYS

UNITED STATES PATENT OFFICE.

JOHN HENRY HAMLIN, OF SALT LAKE CITY, UTAH.

DESIGN FOR A TIP FOR TOOL-HANDLES.

SPECIFICATION forming part of Design No. 28,738, dated May 31, 1898.

Application filed April 26, 1898. Serial No. 678,918. Term of patent 7 years.

To all whom it may concern:

Be it known that I, JOHN HENRY HAMLIN, a citizen of the United States, residing at Salt Lake City, in the county of Salt Lake and State of Utah, have invented and produced a new and original Design for a Tip for Tool-Handles, of which the following is a specification, reference being had to the accompanying drawings, forming a part thereof, in which—

Figure 1 is a side elevation of a tip for tool-handles embodying the features of my design, the tip being shown as applied to the handle of a putty-knife. Fig. 2 is an edge view of the tip and the handle to which it is applied. Fig. 3 is a view of the opposite edge of the tip, and Fig. 4 is an end view of the tip.

The leading feature of the design consists in the shape of the closed end of the tip, which approximates that of a hammer-head, and in a tapering projection from the said end.

The design relates to tips for tool-handles, especially to tips for glaziers' tools. The body A is chambered, and the closed end a of the body is convexed, and upon its convexed surface a tapering projection a' appears. One ²⁵ side edge B of the body is provided with a projecting head-surface b, one side whereof is formed by a portion of the curved surface a. In the opposite side edge C of the body an undercut recess c is formed adjacent to the ³⁰ end of the convexed surface a, which surface above the recess partakes of the delineation of a claw c'.

I claim—

The design for a tip for tool-handles herein ³⁵ shown and described.

JOHN HENRY HAMLIN.
